UNITED STATES PATENT OFFICE.

AUSTIN C. JOHNSON, OF CHICAGO, ILLINOIS, ASSIGNOR, BY MESNE ASSIGNMENTS, TO PRODUCTION METER COMPANY, A CORPORATION OF DELAWARE.

METAL-WORKING SWITCH.

1,136,233.

Specification of Letters Patent. Patented Apr. 20, 1915.

Application filed July 26, 1913. Serial No. 781,293.

To all whom it may concern:

Be it known that I, AUSTIN C. JOHNSON, a citizen of the United States, residing at Chicago, in the county of Cook and State of Illinois, have invented certain new and useful Improvements in Metal-Working Switches, of which the following is a specification.

My invention relates to switches and particularly to switches for making and breaking an electric circuit for operating automatic recording devices which record the period of operation of shop machines upon any particular object.

The object of the invention is to provide a switch of the above character that will be automatically put in operation by vibrations caused by the operation of the machine or tool upon any particular piece of work so that the recording device will record the period of the machine's actual operation upon the work and will automatically break the circuit controlling the recording device immediately upon the completion of the operation.

Another object of the invention is to provide means whereby the circuit connecting the recording device with the source of energy will not be broken during the period of actual operation of the machine and thereby enable the device to record, on a suitable chart, the time consumed for each piece of work with a clear, unbroken line.

A specific object of my invention is to provide a device whereby the vibrations of a tool, especially a metal working tool,—but my invention is not necessarily limited to metal working tools—may be used to actuate a recording device, whereby each period that the tool is in actual operation will be recorded, and particularly to utilize such vibration of the tool or machine, caused by its connecting or similar operation, to close an electric circuit, and to keep said circuit closed during each period of said vibrations, whereby a recording device shall be actuated to record each period when such tool or machine is in active operation.

The invention has as further objects the arrangement, construction and combination of parts and devices hereinafter more specifically described and claimed.

The preferred embodiment of my invention is illustrated in the accompanying drawings, in which like characters of reference 55 designate like parts, and in which—

Figure 1 shows a metal working lathe with my invention applied thereto; and Fig. 2 is a fragmentary view, in elevation, of the lathe tool post, showing my improved 60 switch in section. Fig. 3 shows an embodiment of my invention in which the secondary circuit is eliminated; and Fig. 4 shows a detail view of a preferred form of recording unit to be used in the installation shown in 65 Fig. 3.

Referring to the drawing, 10 designates an ordinary metal working lathe which is provided with the usual head-stock 11 and tail-stock 12 which are provided with live 70 and stationary center points 13 and 14, respectively, between which the work is suspended.

15 designates a carriage adapted to be slid longitudinally on the lathe bed 16, by 75 means of the feed screw 17, operatively connected to the cone pulley 18 by means of the train of gears 19, 20. Mounted on the carriage 15 is a tool supporting post 21 which in operation supports or is engaged by the 80 cutting tool 22.

While I have described generally the above metal working lathe, it will be understood that the specific form of machine is not essential in connection with my invention, as the invention may be used in connection with the machines of various types.

In the drawing, for the purpose of clearly illustrating my invention, I have shown it secured to the tool supporting post 21. 90 While I preferably secure it to the tool post in connection with the type of lathe illustrated in the drawing, its application to that particular member is not essential to its successful operation, as it may be secured to 95 any other suitable part of the machine without impairing its efficient operation. When the invention is applied to the tool post, as shown in the drawing, the post 21 is preferably formed on its side with a boss 23, the 100 face of which is formed with a cavity 24. The diaphragm 25 is placed over the cavity 24 and is held in place by the casing 26 which may be secured to the boss in any

suitable manner, as for example, by screws 27 extending through threaded perforations in the flange 28.

Extending through an aperture in the 5 casing, near the upper edge thereof, is an adjustable contact screw 29 which may be insulated from the casing in any suitable manner, for example by the insulation 30 in the aperture. Extending from the inner 10 face of the casing 26 is a lug 31 to which is pivoted an arm 32. The arm 32 is preferably pivoted near its lower end to the lug 31 and is formed with a curvature so that the lower end of the arm will bear directly 15 against the center of the diaphragm 25. The upper end of the arm is preferably the longer and is bent outward so that the flat portion 33 will stand directly in front of the contact screw 29. The weight of the 20 upper end of the arm, it being the longer and bent outward, holds the lower end against the diaphragm 25 at all times. The contact screw 29 is adjusted to a position so that when the diaphragm is not vibrating 25 the upper end of the arm will normally stand a slight distance away from the end of the screw and so that when the diaphragm vibrates, as hereinafter described, the upper end of the arm will be brought into a series 30 of rapid contacts with the end of the screw. Connecting the contact screw 29 with a generator 34, or any other suitable source of energy, is a wire 35 in which is interposed a retarding relay 36, that is to say, 35 a relay of the type which will retain its energy for a short time after the circuit has been broken. The wire 37 extends from the generator 34 and is grounded on the tool post 21, completing the circuit between the generator and the switch. Another circuit 40 is formed by wires 38, 38^a and 39 which connect a recording device 40 with the generator.

The recording device in this application 45 is described and claimed in my copending application Serial No. 719,937, filed September 12, 1912, and will not be described in this connection, it being understood that upon closing the circuit connecting it with 50 the generator its mechanism is energized and operates the arm 41 so as to record, on a suitable chart, the time spent on each piece of work passing through the machine. The circuit connecting the recording device is 55 preferably closed by means of an armature which is connected to wire 38 and pivoted to a suitable support 43 on the base 44 so that upon energizing the relay 36, the armature is drawn over against the screw 45 and 60 directs the current through the U-shaped member 46 and the wire 38^a to the recording devices. To facilitate the adjustment of the armature I preferably provide a screw 47 which extends through insulator 48 in an 65 aperture in the U-shaped member 46.

The operation of the device may be briefly described as follows: Immediately upon the cutting tool 22 starting to operate upon any object suspended between the center posts 13 and 14, or otherwise secured to the machine, the diaphragm 25 is thereby caused to vibrate. The vibrations of the diaphragm operate the arm 32 so as to bring it into a series of rapid contacts with the contact screw 29, which in turn rapidly makes and 70 breaks the current between the switch and the generator 34, the wires 37 being connected to the tool post 21. When the above circuit is closed the relay 36 is energized and draws the armature 42 over against the 75 contact 45 and closes the circuit connecting the recording device with the generator. The relay 36, being of the type which retains its energy for a slight period of time after the circuit in which it is connected has 80 been broken, will hold the armature 42 against the contact 45 during the slight intervals that the arm 32 is out of contact with the contact screw 29 during said rapid vibrations and thereby enable the recording 85 device to record on its chart with a clear, unbroken line the exact time during which the tool is actually doing any work.

While I have described my invention in its preferred embodiment, it will be understood that modifications might be made without departure from the spirit of the invention. Therefore, I do not wish to limit myself to the particular form described except so far as limited by the claims herein.

While, for purposes of illustrating a certain specific complete installation of my invention in an apparatus involving what may be called an energizing circuit and a recording circuit, nevertheless, it will be noted that, broadly, my invention consists in the combination with an electrical circuit, of a retarding relay interposed therein, a switch in said circuit combined with a machine or tool in such a manner that the vibrations of said machine or tool, caused by its effective operation, will cause said relay to be continuously energized during each period of such vibrations whereby the armature of said relay is held in a certain position for any useful purpose, and although, in the specific embodiment shown and described, the movement of the armature of said relay is utilized to open and close the circuit directly connected to the recording machine, it is obvious that the recording apparatus might be connected directly to the armature of a retarding relay and be within the broad disclosure of my invention, as above defined. Therefore, it should be understood that I 110 broadly disclose the above broadly defined apparatus for moving the armature of the retarding relay for any useful purpose, of which the actuation of the recording mechanism may be either by closing a secondary 115 120 125 130

circuit or by direct mechanical connection between the armature of the relay and the recording device.

It should be understood that the machine 5 of my copending application is preferably, for commercial convenience, designed according to a standard construction adaptable for use with all types of shop machines and that the recording and accumulating 10 units thereof, indicated at 40 in the drawings of the present application, are preferably made of a standard type. Inasmuch, therefore, as for use with numerous shop machines it is undesirable that the solenoids 15 of the unit 40 should be of the retarding type, preferably, therefore, these units should be interposed in a secondary circuit as shown, but it is quite within the contemplation of my invention that the secondary 20 circuit be eliminated and that the unit 40 be provided with solenoids or relays of the retarding type and be interposed directly in the primary circuit, as shown in Figs. 3 and 4. Thus, in Figs. 3 and 4 I have shown 25 my invention broadly with the secondary circuit eliminated. In this installation the preferred form of recording unit may be the same as that shown in my second copending application and is identical with 30 the unit indicated in Fig. 1, except that the solenoids are of the retarding type; that is, they are constructed in a manner well known in the art; whereby when energized they all retain their energy an appreciable 35 time after the energizing circuit has been broken. Fig. 4 shows only so much of said unit in detail as is necessary to understand its operation to actuate the recording arm, which is rigidly secured to the armature 41.

40 Wherever, in the specification or claims, I refer to the "efficient" operation of the tool or machine, I mean its actual operation in performing the work for which it is intended as distinguished from running idle.

45 Wherever in the claims I refer to "vibration" I mean the above described bodily vibration of a tool, machine or portion thereof and the corresponding vibration produced thereby in the diaphragm as distinguished 50 from any traveling movement capable of transmission by intermediate and differently moving parts which might literally come within the broad meaning of the term "vibration."

55 I claim:

1. A device of the character described, comprising a diaphragm so connected with a shop machine as to be vibrated by the vibration of the shop machine caused by the 60 operation thereof, and means engaging said diaphragm and actuated by the vibrations thereof to make and break an electric circuit.

2. An automatically operated switch, 65 comprising a diaphragm directly connected

with a shop machine so as to be actuated by the vibration of the shop machine caused by the operation thereof, and a pivoted arm engaging said diaphragm and actuated thereby to produce a rapid make and break 70 of an electric circuit.

3. In an automatically operated switch of the character described, the combination with a shop machine and an electric circuit, of a diaphragm interposed in said circuit 75 and in such operative relation to said machine as to be actuated by the vibration of the shop machine caused by the operation thereof; and a pivoted arm operated by said diaphragm when so vibrated, to open and 80 close said circuit.

4. The combination with a recording circuit and a shop machine circuit, of a shop machine, a diaphragm in such operative relation with the shop machine as to be vibrated by the vibration of the shop machine caused by the operation thereof so as to rapidly make and break said shop machine circuit, and means whereby said recording circuit will be continuously closed 90 during the vibration of said diaphragm.

5. In a device of the character described, the combination with a metal working lathe and an electric circuit, of a diaphragm in such operative relation to said lathe as to 95 be vibrated by the vibration of a portion of said lathe caused by the metal working operations of said lathe, and means operated by the vibration of said diaphragm to produce a rapid make and break of said circuit. 100

6. The combination with a shop machine of a source of electrical supply, a recording device, controlling means for said recording device in circuit with said supply, and means actuated by the vibration of said 105 shop machine caused by the operation thereof for closing said circuit.

7. The combination with a shop machine of a source of electrical supply, a recording device, controlling means in circuit with 110 said supply for controlling said recording device, and vibrating means in operative relation with said shop machine so as to be vibrated by the vibration of a part of said shop machine caused by the operation thereof 115 for automatically causing a continuous closure of said circuit during each such period of vibration.

8. The combination with a shop machine of a recording device, a source of electrical 120 supply, actuating means for said recording device in circuit with said source of electrical supply, controlling means for making and breaking said circuit, and means in operative relation to said shop machine for 125 making and breaking an electrical circuit between said controlling means and said source of supply, comprising a diaphragm in operative relation with said machine so as to be continuously vibrated by the vibration of 130

said machine caused by the operation thereof, and means in engagement with said diaphragm adapted to be operated by the vibrations thereof to make and break the said 5 last named circuit.

9. In an automatically operated switch for opening and closing an electrical circuit, the combination with a metal working lathe provided with a tool holding member, of a 10 casing secured to said tool holding member and provided with a contact plug, an arm pivoted in the casing, a diaphragm interposed between the casing and the tool holding member adapted to be vibrated by the 15 vibration of the tool-holding member when the tool is in operation, one end of said pivoted arm being adapted to engage the dia- 20 phragm so that the vibration of said dia- phragm will bring the other end of said arm into and out of contact with said contact plug.

10. In an automatically operated switch for opening and closing an electrical circuit, the combination with a metal working lathe 25 provided with a tool holding member formed with a cavity, a diaphragm secured over said cavity so as to be vibrated by the vibration of the tool-holding member when the tool is in operation, a casing secured to said 30 tool holding member and provided with a contact plug of said electrical circuit, and an arm pivoted to said casing provided at one of its ends with a bent portion engaging the center of said diaphragm and the other 35 end extending over the said plug so that the vibration of the diaphragm will cause it to move into and out of contact with said contact plug.

11. The combination with a machine or 40 tool, of an electric circuit, a retarding relay interposed in said circuit, an armature for said relay, and means interposed in said circuit whereby the vibrations caused by the efficient operation of said tool or machine 45 will cause said relay to be continuously energized during each period of such vibrations,

whereby said armature is attracted toward said relay for any desired purpose.

12. The combination with an electric circuit, of a retarding relay interposed therein, 50 an armature therefor, a recording device ar- ranged to be actuated by the movement of said armature, a tool or machine, and means interposed in said circuit whereby the vi- 55 brations caused by the efficient operation of said tool or machine will cause said circuit to be sufficiently closed to continuously ener- gize said relay during each period of said efficient operation, whereby said armature is moved toward said relay, thereby causing 60 said recording device to be moved to and held in a certain position during each such period.

13. The combination with an electric cir- 65 cuit, of a retarding relay interposed therein, an armature therefor, a recording device adapted to be actuated by the movement of said armature, a machine or tool, a switch interposed in said circuit, and a diaphragm in operative engagement with said machine 70 or tool and with said switch, whereby the vibrations of said machine or tool produced by the efficient operation thereof will cause said diaphragm to actuate said switch to so close said circuit that said relay will be con- 75 tinuously energized during each such period of efficient operation and said armature will thereby be moved and held from its normal position, causing said recording device to be moved to and held in recording position. 80

14. The combination of a shop machine having a part which is vibrated by produc- 85 tive operation of said machine, a diaphragm mounted on said machine so as to be vi- brated by the vibration of said part, and means engaging said diaphragm, adapted to open and close an electric circuit.

AUSTIN C. JOHNSON.
